UNITED STATES PATENT OFFICE

2,432,402

ASH RECEIVER FOR DESKS

Benton L. Fay, St. Joseph, Mich.

Application November 7, 1946, Serial No. 708,221

4 Claims. (Cl. 232—1)

1

This invention relates to improvements in ash receivers for desks.

The main objects of this invention are:

First, to provide an ash receiver for desks which is supported so that it does not obstruct the top of the desk, cannot be upset by the movement of papers and objects on the desk, and at the same time is readily accessible.

Second, to provide a structure having these advantages which is neat and attractive in appearance.

Further objects relating to details and economies of the invention will appear in the description to follow. The invention is defined in the claims.

A structure which embodies the features of the invention is illustrated in the accompanying drawing, in which:

Fig. 1 is a fragmentary view in vertical section on a line corresponding to line 1—1 of Figs. 2 and 3, the ash receptacle being shown in partially withdrawn position by dotted lines.

Fig. 2 is a fragmentary plan view.

Fig. 3 is a plan view showing the general relation of the parts to a desk which is conventionally illustrated, parts being shown by dotted lines.

The embodiment of my invention illustrated comprises the desk top 1 having a chamber 2 below the top, the wall 3 constituting one wall of the chamber, this wall 3 being a side wall of the knee hole. The top 1 has an opening 4 therein communicating with the chamber 2. The opening 4 is surrounded by the recess 5 having an upwardly facing peripheral groove 6. The concave receiver 7 is seated in the recess 5 and has a downturned flange 8 engaging the groove 6. The top of the receiver is flush with the desk top.

The receiver has a delivery spout or tube 9 projecting into the chamber 2. The wall 3 has an opening 10 therein adapted to removably receive the cylindrical receptacle 11 which has a top opening 12 aligned with the spout 9 to receive the material discharged through the spout. The receptacle 11 has a closed inner end 13 and a partition 14 adjacent its outer end. The receptacle is provided with an end member 15 provided with a flange 16 engaging the outer side of the wall 3. This end member and the partition 14 coact to provide a chamber 17 in which the bolt housing 18 is arranged, the bolt housing being mounted on the inner side of the end member 15. The bolt 19 is slidably arranged in the housing 18 and is biased by the spring 20 arranged at the inner end of the bolt so that the

2

bolt is normally projected into engagement with the keeper 21 mounted in the wall 3 at the bottom of the opening thereof. The end member 15 is provided with a stem-like finger piece 22 which is recessed on its under side at 23 to receive the bolt actuating lever 24 which is pivoted at 25 at the outer end of the recess and pivotally connected at 26 to the bolt. Thus arranged, when the grip or finger piece 22 is grasped to remove the receptacle, the lever 24 is actuated to retract the bolt permitting the withdrawal of the receptacle.

The receiver 7 is provided with a depressed portion or downwardly offset portion 26 at one side of the spout having a hole 27 therein adapted to receive the quenching well 28 which has a flange 29 at its upper end. This quenching well is externally threaded at 30 to be threaded into the nut 31 which is secured to the under side of the receiver. The quenching well flange 29 has finger notches 32 which makes it convenient to grasp for removal for cleaning. This quenching well is designed to contain water so that cigarettes or cigars may be extinguished before they are dropped into the receiver.

With this arrangement of parts the top of the desk is not obstructed. The receiver may be conveniently located and cannot be upset by objects placed on the desk.

I have illustrated and described my improvements in an embodiment thereof which I find highly satisfactory. I have not attempted to illustrate or describe various embodiments or adaptations which I contemplate, as it is believed that this disclosure will enable those skilled in the art to embody or adapt the invention as may be desired.

Having thus described my invention, what I claim as new and desire to secure by Letters Patent is:

1. The combination in a desk including a top and a chamber below the top having a side wall, the side wall having an opening therein communicating with said chamber, the top having an aperture therethrough surrounded by a recess and an upwardly facing groove, of a concaved receiver disposed in said recess and having a downwardly projecting peripheral flange disposed in said groove, the receiver having a central discharge spout depending into said chamber, an ash receptacle removably supported in said wall opening and having an opening in the top thereof through which said spout discharges, said receptacle having a flanged end member provided

with a grip and arranged to locate the opening in said receptacle under said discharge spout.

2. The combination in a desk including a top and a chamber below the top having a side wall, the side wall having an opening therein communicating with said chamber, the top having a recess therein surrounded by an upwardly facing groove in its outer edge, of a concaved receiver disposed in said recess and having a downwardly projecting peripheral flange disposed in said groove with the top of the receiver flush with the desk top, the receiver having a central discharge spout depending into said chamber, an ash receptacle removably supported in said wall opening and having an opening in the top thereof through which said spout discharges, said receptacle having a flanged end member provided with a grip, said receptacle being provided with a partition spaced from said end member to provide a bolt chamber, a spring biased bolt arranged in said bolt chamber to project therefrom, a keeper mounted on said wall to coact with said bolt, said end member having a bolt lever receiving recess therein, and a bolt actuating lever disposed in said recess and pivotally connected to said bolt and end member.

3. The combination in a desk including a top and a chamber below the top having a side wall, the top having a recess therein surrounded by an upwardly facing groove at its outer edge, of a receiver disposed in said recess and having a downwardly projecting peripheral flange disposed in said groove with the top of the receiver substantially flush with the desk top, said receiver having a discharge spout depending into said chamber, an ash receptacle removably mounted on said wall to project into said chamber to re-

10

15

20

25

ceive the discharge from said spout, said receptacle having a flanged end member, a spring biased bolt carried by said receptacle, a keeper mounted on said side wall to coact with said bolt, a grip on said receptacle projecting from said flanged end member when the receptacle is mounted thereon, and a bolt retracting lever pivotally mounted on said grip so that the bolt may be disengaged by the operator grasping the grip.

4. The combination in a desk including a top and a chamber below the top having a side wall, the top having a recess therein surrounded by an upwardly facing groove at its outer edge, of a receiver disposed in said recess and having a downwardly projecting peripheral flange disposed in said groove with the top of the receiver substantially flush with the desk top, said receiver having a discharge spout depending into said chamber, an ash receptacle removably mounted on said wall to project into said chamber to receive the discharge from said spout, and a flanged end member on said receptacle and provided with a hand grip, the flange on said end member being arranged to engage said side wall to locate said receiver under said spout.
